W. P. WEBER

MECHANICAL SUGAR SPRAYER

Filed Dec. 29, 1922

Inventor

10 William P. Weber
by Wilkinson & Giusto
Attorneys.

UNITED STATES PATENT OFFICE.

WILLIAM P. WEBER, OF WHITE CASTLE, LOUISIANA.

MECHANICAL SUGAR SPRAYER.

Application filed December 29, 1922. Serial No. 609,654.

To all whom it may concern:

Be it known that I, WILLIAM P. WEBER, a citizen of the United States, residing at White Castle, in the parish of Iberville and State of Louisiana, have invented certain new and useful Improvements in Mechanical Sugar Sprayers; and I do hereby declare the following to be a full, clear, and exact description of the invention, such as will enable others skilled in the art to which it appertains to make and use the same.

The present invention relates to improvements in mechanical sugar sprayers and has for its purpose to provide for the washing of sugar in a centrifugal.

Other objects of the invention are to produce a device for purging the sugar crystals while in the centrifugal and just after the act of separation has taken place; to provide in conjunction with the centrifugal a spraying pipe adapted to be let down into the centrifugal without interfering with its continuous rotation, into which pipe water under pressure is sprayed through the sugar crystals; in providing in conjunction with the pipe and a tank and connections to receive a supply of water and to place the water under appropriate pressure and to furthermore provide for the introduction of steam for cleansing the parts; and to provide a compact, simple and inexpensive device for the purpose stated.

With the foregoing and other objects in view, the invention will be more fully described hereinafter, and will be more particularly pointed out in the claims appended hereto.

In the drawings, wherein like symbols refer to like or corresponding parts throughout the several views,

The figure is a side elevation, with parts shown in section of the improved devices illustrated in conjunction with a centrifugal which is shown in vertical section.

Referring more particularly to the drawings 1 designates a centrifugal having the rotary basket 2 in which the sugar crystals are indicated at 3 as arranged in a layer or zone against the wall of the basket by virtue of the centrifugal force. Assume that the molasses has just been separated and that the centrifugal is in readiness to discharge the sugar crystals.

The portion of the machine or stand 4 is adapted to receive a bracket arm 5 connected thereto as by a bolt or

other fastening 6 passing through the angled end of the bracket arm; and this bracket arm at its free end is adapted to overlie the central portion of the centrifugal basket and at this point said arm is perforated to receive the brass or other bushing 7, secured to the bracket arm as by the lock nut 8 threaded thereon and bearing against the under side of the bracket. Through this bushing extends slidably a pipe 9 having numerous perforations 10 therein which preferably extend in rows spaced angularly about the pipe and adapted to throw minute streams horizontally against the layer of sugar crystals 3 while the centrifugal 2 is rotated. The pipe 9 is adapted to extend within a short distance of the base of the centrifugal and at its lower end is closed or blocked to avoid the escape of the wash water. At its upper end the pipe telescopes over a supply pipe 11 of lesser diameter, there being a stuffing box 12 at the upper end of the distributor pipe 9 to avoid leakage and to provide a tight joint. The gland nut 13 may be removed from time to time to insert fresh packing. The stuffing box 12 forms a suitable enlargement upon the upper end of the pipe to which to attach a relatively large and weighty handle 14 by which the distributor pipe may be raised to the position indicated in dotted lines. Here the handle is engaged with a hook 15 suspended from a collar 16 carried upon the horizontal pipe 17 which is connected by the elbow 18 to the vertical supply pipe 11.

The base of the supply pipe 11 which is open and in communication with the interior of the distributor pipe 9 should be just above the uppermost of the perforations 10 when said distributor pipe is in the lower position. The horizontal pipe 17 may be of any suitable length and provided with suitable unions such for instance as 19 and said pipe connects as by an elbow 20 with a three way valve casing 21, the upper branch of which is connected to the base of the tank 22. The third branch of the casing 21 is connected to a water supply as indicated and a valve arm 23 is provided to either put the tank 22 in communication with the water supply or place the tank 22 in communication with the pipe 17. The tank carries connections 24 and 25 for the attachment of a glass gage tube 26 to show the condition within the tank

and the tank will be supported suitably for instance by a bracket 27 attached to the standard or frame 4 considerably above the bracket 5. At the top of the tank is a second three way valve casing 28 having the valve operating arm 29 and being attached at its top branch to an overflow pipe 30 and at its intermediate branch to a source of compressed air or steam indicated at 31.

10 Now parts may be of suitable sizes and material to meet the requirements of any given case and the operation is as follows:—

When the process of separation in the centrifugal basket 2 is finished and the sugar crystals are in readiness to be washed, the heavy handle 14 is disconnected from the hook 15 and the distributor pipe 9 is allowed to descend through the bushing 7 until it arrives at a lower position within the centrifugal whereupon the lower portion of the packing box will abut upon the upper flanged end of the bushing 7 and arrest a further downward movement. The valve handle 23 of the valve casing 21 is turned 25 for instance in the position indicated to place the water supply in communication with the tank 22 and a suitable amount of water is allowed to enter the tank; the amount being shown by the gage 26. Subsequently the 30 valve handle 29 of the upper casing 28 will be turned appropriately to permit the entrance of compressed air above the water in the tank. The water will then be allowed to flow down into the pipe 17 by shifting the 35 valve handle 23 and the water will descend under considerable pressure through the vertical supply pipe 11 and into the distributor pipe 9, issuing under force out of the minute perforations 10 in small jets or streams 40 which impinge against the sugar crystals and purge the same. This action is allowed to go on for a period of time while the centrifugal is rotated, and in this way sugar crystals are thoroughly washed before being 45 discharged. As soon as the washing operation is over the distributor pipe 9 is lifted out of the centrifugal so as to avoid interference with future operations and it is held suspended by the engagement of the handle 50 14 with the hook 15. The overflow 30 is opened and the tank is preferably never completely filled in order to leave a suitable space for the head of air above the water column. When it is desired to clean the 55 parts, the air supply may be disconnected and the steam supply coupled hereto and steam under pressure circulated throughout the system.

These operations are repeated from time

to time and the device will be found very desirable as saving considerable time and providing for the effective purging of the sugar crystals. The handle 14 fits over the hook 15 and the hook may be slid along the horizontal pipe. Of course any arrangement of hook and handle may be used.

It is obvious that various changes and modifications may be made in the details of construction and design of the above specifically described embodiment of this invention without departing from the spirit thereof, such changes and modifications being restricted only by the scope of the following claims.

What is claimed is:

1. A mechanical sugar sprayer comprising in combination with a centrifugal machine having a rotary basket, a bracket supported by the machine over the basket, a distributor pipe, having minute perforations arranged 80 in rows, slidable through said bracket and into the centrifugal, a stuffing box on the upper end of said pipe adapted to arrest its movement before striking the bottom of the basket, a supply pipe fitting telescopically 85 within said distributor pipe, said distributor pipe being movable upon said supply pipe, a horizontal pipe connecting with said supply pipe, a hook suspended from the horizontal pipe, a weighty handle carried by the 90 stuffing box and positioned to engage said hook, and a tank being in connection with a source of water supply and air under pressure supply communicating with said horizontal pipe.

2. A mechanical sugar sprayer comprising in combination with a centrifugal machine having a rotary basket, a bracket supported by the standard of the machine and overlying the inner part of the basket, a bushing in said bracket coaxial with the basket, a perforated distributor pipe of large diameter 100 slidable through said bushing into and out of the basket, a stuffing box on the upper end of said distributor pipe adapted to rest on said bushing and having the weighty handle adapted thereto, a supply pipe of relatively small diameter fitting within said distributor pipe, a horizontal pipe coupled to said supply pipe and having a hook adapted to engage said handle, a tank supported by said machine and being in connection with said horizontal pipe, an overflow for said tank, and upper and lower valves for the tank being in connection respectively with a source of compressed air, steam and water supplies.

WM. P. WEBER.
